CLAIM

The ornamental design for bottle lid, as shown and described.

DESCRIPTION

FIG. 1 is a top, front perspective view of an implementation of a bottle lid in a closed configuration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 a top, front, perspective view thereof coupled to a bottle body;

FIG. 9 is a top, front perspective view of an implementation of a bottle lid in an open configuration;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 a top, front, perspective view thereof coupled to a bottle body.

The broken line showing of the bottle body in FIGS. 8 and 16 is for the purpose of illustrating environmental structure and forms no part of the claimed design. All other broken lines represent unclaimed features of the article to which the design is applied.

1 Claim, 10 Drawing Sheets
